PRINTING MACHINE

Frank C. Marquardt, Bronx, N. Y., assignor to
 American Bank Note Company, New York,
 N. Y., a corporation of New York

Application August 31, 1943, Serial No. 500,602

13 Claims. (Cl. 91—50)

This invention relates generally to printing machines and has particular reference to improvements in mechanism for supplying a printing composition such as wax carbon in fluid condition to the impression faces of printing elements.

One object of the invention is to make it possible to use a printing press of the plate cylinder type for what is known in the art as spot carbon printing, although, as will be appreciated later on, the improvements are not limited in their application to that particular type of press. The term spot carbon printing is used broadly to cover the application of manifolding carbon only to the desired parts of sheets of paper making up a manifolding set as distinguished from an all-over coating. Usually, the carbon is so applied that there will be a coating on the back of the paper which conforms generally in area, extent and location to a space or spaces on the face of the paper provided for the writing of matter which will be reproduced by the carbon on the next sheet in the manifolding set. Usually the purpose of spot carbon printing is to economize in the use of carbon, although there are instances where only a certain part of matter written on the face of an instrument needs to be reproduced on a manifold copy to make a record.

The plate cylinder type of printing press has many desirable characteristics such as simplicity of construction and operation, coupled with the fact that it lends itself to accurate work by locating the imprints on successive sheets of paper with great uniformity. Further, the printing plate used in plate cylinder machines may readily be etched, engraved or otherwise treated to give any desired number of printing faces of any desired shapes or extents. However, the inking mechanisms heretofore used on such printing machines are not suitable for wax carbon printing due principally to the characteristics of that material. It is normally a solid composition of wax, oil and coloring matter which is made fluid enough to print by heating it above its melting point or to a point where it has the consistency of a fairly stiff varnish when it is applied to the printing faces and transferred from those faces to the paper. This, of course, involves both melting the wax carbon and keeping it at the proper temperature until the printing is completed.

An important object of the invention is to provide a mechanism which will heat the wax carbon until it is of the proper consistency and maintain it in that condition until the printing impression is made. This is accomplished by a novel heating apparatus which includes a set of manual controls for independently regulating sets

of heating elements suitably positioned to apply the proper degrees of heat to melt the wax carbon and to keep it hot during its transit to the paper.

5 Another object of the invention is to provide a novel mechanism for heating and applying the wax carbon to the printing faces of a printing plate or similar instrumentality. It is constructed as a unit which is movable as a unit by manually-controlled throw-off devices when printing is to be discontinued, and can be removed as a unit from the press for cleaning or any other purpose. All of the parts remain in position and adjustments need not be disturbed, and after it is ready to be again placed in operation it is moved as a unit back into the position where it applies the wax carbon to the printing faces of the printing plate.

Without further particularizing, the invention attains other objects and has other advantages which will be apparent from the description hereinafter contained. As will also become apparent, the invention consists in a novel combination and relation of parts, an illustrative embodiment of which is shown in the drawings accompanying and forming a part of this specification, the novel features of the invention being recited in the claims appended hereto.

In the said drawings:

Fig. 1 is a side view of a printing press of the plate cylinder type equipped with the improvements disclosed in this application.

Fig. 1a is a detail of a toggle forming a part of the throw-off mechanism for the wax carbon supply.

Fig. 2 is a side view of the wax carbon supplying unit on the line 2—2 of Fig. 5.

Fig. 3 is a cross-section on line 3—3 of Fig. 5.

Fig. 4 is a detail viewed from line 4—4 of Fig. 2, of an adjustment for the doctor blade employed to regulate the thickness of the carbon which is applied to the paper.

Fig. 5 illustrates many details of the roller mechanism and the gearing for supplying heated wax carbon to the printing faces of the printing member.

Fig. 6 shows parts of a section, on the line 6—6 of Fig. 2, of the lower electrically heated roller employed.

Fig. 7 is an end view partly broken away of the apparatus shown in Fig. 6.

Fig. 8 is a section illustrating the internal construction of the upper heated roller.

Fig. 9 is a section on the line 9—9 of Fig. 5.

Fig. 10 shows principal details of the construction of the plate cylinder impression cylinder,

and shows the heating elements associated with the plate cylinder.

Fig. 11 is an end view of the machine that is, as viewed from the left of Fig. 1, with parts thereof broken away.

Fig. 12 is a section on the line 12—12 of Fig. 11, and illustrates details of the throw-off mechanism for the plate cylinder.

Fig. 13 is a section through the plate cylinder throw-off mechanism on the line 13—13 of Fig. 12.

Fig. 14 illustrates details of the manual control of the plate cylinder throw-off mechanism, this same control being effective to operate the throw-off mechanism for the carbon heating and supplying mechanism.

Fig. 15 is a section on the line 15—15 of Fig. 14.

Figs. 16 and 17 illustrate diagrammatically layouts of printing plates.

Figs. 18 and 19 illustrate some of the many carbon spots which may be applied by suitable construction of the printing plates.

Fig. 20 is a wiring diagram of the electrical control for the various heating elements.

Fig. 21 is a diagram of the panel board for the electrical equipment.

In the drawings, the various features of the invention are shown in the form they have when applied to a plate cylinder printing press. It is constructed to print carbon spots upon hand-fed sheets, the location, area and shape of the spots being determined by the construction and position of printing faces on a printing plate attached to the printing cylinder and cooperating with an impression cylinder. Power for driving the apparatus is supplied by a motor 30, Fig. 1, and a belt or chain 31 driving a large pulley or sprocket 32 which is rigid with a small gear 33. All of the driven parts of the machine derive their power through the connections just stated.

The printing couple consists of two cylinders 34, 35, Figs. 1 and 10, between which the sheets of paper are fed, the cylinder 34 being the impression member of the couple, and the cylinder 35 the plate-carrying or printing member of the couple. Sheets of paper are fed in from a feed board 36 against the usual stop or gauge 37 in which position the edge is received by a gripper designated generally as 38, and the sheet then travels with the cylinder 34 until the gripping device is operated to release it. The gripping device is of the tumbler type actuated by a spring 39 and stationary pin 40 which has been used for many years on sheet printing cylinder presses and need not be described in detail.

The machine also has the usual set of tapes 41, 42 and 43, Fig. 1, for holding the sheet against the periphery of the impression cylinder 34 and then after the gripping device has released the leading edge of the sheet, directing the sheet onto the fly 44. This fly is old in sheet printing machines and need not be described in detail. It is sufficient to say that it is actuated by a chain 45 which runs over a sprocket 46 rigid with the fly and a guide sprocket 47 and which is moved in one direction by a rotary cam 48 and bell crank 49 and in the other direction by a return spring 52. The cam 48 is so constructed as to swing the fly 44 on its pivot 53 once for each rotation of the cylinders 34 and 35, the fly depositing the printed sheet on the table or stack 54 in the usual way.

The impression cylinder 34 has its effective surface covered by a rubber sheet 55, Fig. 10, which may be of any required thickness, backed up by a paper underlay 56. The rubber sheet

and the paper underlay are secured in any suitable way at one of their edges to the impression cylinder 34 and their other edges are secured to the usual shafts 57 and 58 having squared ends 5 to accommodate a wrench and ratchets 61 and 62 by which tension may be applied to insure a smooth fit of the underlay and rubber sheet on the cylinder. The usual brush 62a contributes to that effect, although its primary purpose is to insure that the sheets of paper are in close and uniform contact with the rubber sheet 55.

The plate cylinder 35 carries a plate 63 which is constructed to provide printing plate faces for printing the desired carbon spots. It is preferably an etched zinc plate having the printing faces in relief, as illustrated diagrammatically at 64 in Figs. 16 and 17. In a representative machine the zinc plate has a thickness of about .039" and is deep-etched to a thickness of about .022" except for the printing faces 64 which are not affected by the etching and have the original thickness of the plate. An underlay 65, Fig. 10, of paper or any other suitable material is employed over which the etched zinc plate is secured by clamps 66 and 67 which are so constructed as to draw the plate taut around the cylinder as an incident to securing it in position. This construction is disclosed in U. S. Patent No. 1,374,859, issued April 12, 1921, to the present applicant.

It will be understood, of course, that in etching the printing plate it will have the printing faces 64 repeated or duplicated upon the plate as required for printing sheets which are later to be cut up into the required blanks.

The heated carbon is applied to the printing faces of the printing plate by a roll or rollers 68. There may be a single roller extending all the way across the printing plate 63, but usually, as shown in Fig. 5, there may be a plurality of rollers or roller sections each applying the carbon only to a part of the printing plate. The roller or rollers 68 constitute a part of the carbon heating and applying mechanism which, as before indicated, is a unit which can be withdrawn as a unit from relation with the printing plate 63 and which is operated as a unit when it is desired to throw off the carbon mechanism during printing operations. This throw-off mechanism will be described in detail later on.

Whether a single roller or a plurality of shorter rollers is employed, they are attached to a shaft 71 which has its ends rotatably supported in slots 72 of elements 73, Figs. 2 and 5. Each of said elements has an extension 74 slidable in a boss 75 on a member 76 which can be adjusted around a bushing 77 in which is mounted a shaft 78 carrying a roller 121 described in detail later on. The member 73 may be adjusted by turning the head 81 of a screw 82 which is threaded into a boss 80 on the member 73 to raise and lower the member 73. After the adjustment of the member 73 has been made it may be secured by a set screw 79 extending at an angle through the boss 80 into contact with the extension 74. The screws 82 are employed in levelling the roller or rollers 68 horizontally so as to make the proper contact with the full width of the roller 121.

The adjustment of the rollers 68 radially with reference to the plate cylinder 35 to regulate the inking pressure is effected by screws 88 (Fig. 2) turning in bosses 89 on the machine framework. Each screw may be turned up or down with reference to a slotted ear 91 integral with the member 76. After the desired adjustment of the screws 88 has been made, the adjustment can be

secured against disturbance by a set screw 83 extending through a slot 84 of the ear 91 and into a threaded hole in the adjacent machine frame.

From the foregoing it is believed to be clear that the screws 82, 82 are first operated to line up the rollers 68 horizontally so that they will be parallel to and in contact with the roller 121 and that the adjustment including the screws 88 is then made to regulate the inking contact of the roller 68 with the printing plate. In describing these adjustments the parts have occasionally been referred to in the singular, but it will be understood that the adjustments are duplicated on each side of the machine. This construction is more fully disclosed in United States Patent No. 1,558,108 issued October 20, 1925, to the present applicant.

The roller or rollers 68 for applying the carbon to the printing plate are, for convenience, usually referred to from now on as the inking roller.

The carbon which is applied by the inking roller is supplied from a font designated generally as 92 in Figs. 1, 2 and 3. It includes spaced-apart side frames 93 and tie-rods 94 between which is a sheet metal tray or pan 95 in which the supply of wax carbon is deposited. The sheet metal pan has a drain 96 for use in emptying the pan whenever desired. Heat for melting the carbon in the pan is supplied by a series of electric heating elements 97 of the strip type which pass close to and across the bottom of the pan 95. They do not need to be shown or described in detail as they are standard commercial units now on the market and widely used for similar purposes. They are connected to a source of current by leads opened and closed by a switch 98, Figs. 20 and 21, and the amount of heat developed by the heaters 97 is regulated by a rheostat 99. In normal operations the heat applied is sufficient to melt the wax carbon in the pan 95 and maintain it at a temperature at which it has a consistency approximating that of a fairly heavy varnish. The exact temperature is not critical, as there are other means described later on for applying heat which can be regulated to give the wax carbon the desired consistency when it is applied to the printing plate 63.

Rotatably mounted in the font and about half submerged in the melted wax carbon are two parallel rollers 101 and 102 which are driven in opposite directions by the gearing hereinafter described, roller 102 turning clockwise and 101 counterclockwise as viewed in Fig. 3. The roller 102 is heated electrically while the roller 101 is not heated except by the hot carbon. The rollers 101 and 102 are so set that there is a crevice of about .010" between them. They lift the melted wax carbon from the pan 95 and cooperate mutually and with the walls of the side plates 93 to create and maintain a pool 103 of the melted carbon which is above the level of the carbon in the pan 95 and from which pool the carbon to be transmitted to the printing plate is drawn. Advantages of the rollers 101 and 102 and the pool 103 are that the carbon is maintained at a constant level in the pool instead of being lowered as the carbon is used, and the relatively small amount of carbon in the pool makes it easy to control the consistency of the carbon within accurate limits by regulating the heat supplied to the pool by the roller 102.

The roller 102 is attached to a hollow shaft 104 journalled in the side plates of the font. As shown in Figs. 3, 6 and 7, the hollow in the shaft is used to accommodate a tubular heater 105

which is connected by leads 106 and 107 to a pair of properly insulated commutators 108 and 109 which are in contact with brushes 111 and 112 connected to a source of current. The connection to the current source is controlled by a switch 113, Figs. 20 and 21, and the amount of heat is controlled by a manually adjustable rheostat 114. The amount of heat developed in the shaft 104 and within the roller 102, which is hollow, is sufficient to maintain the carbon at the temperature it is given by the heating elements, or, of course, there may be an adjustment either way of the amount of heat to get the effect desired.

15 The roller 101 is likewise a hollow roller and is attached to a shaft 116 journalled in the side plates of the font. As a matter of convenience in assembling, the shaft 116 and the shaft 104 for the roller 102 are supported in the bottoms of slots 117 in the side plates 93 and are held against accidental disturbance by keepers 118 each having a sliding tongue and groove (not shown) engagement of its edges with the edges of the slots 117. This makes it possible to remove the rollers 101 and 102 without having to disassemble the whole unit.

20 Also mounted in the side plates of the font is the roller 121 previously mentioned which has a limited part of its periphery in contact with the wax carbon in the pool 103.

25 As the roll turns it will be coated with the wax carbon and the carbon transmitted to the inking roll 68. The roller 121 is hollow and contains a set of electric heater units 122. The units are of the kind known as hair-pin heaters, they being mounted or held in place by supports 123 within the roller as shown in Fig. 8. The heaters are connected by suitable wiring to insulated commutators 125 and 126 on the 30 end of the shaft 78 to which roller 121 is secured, the commutators 125 and 126 being engaged respectively by brushes 127 and 128. The shaft 78 is hollow to facilitate wiring the heaters to the commutators. The brushes are of course connected by suitable leads to a source of current supply. The connection to the current source is controlled by a switch 131, Figs. 20 and 21, and density of the current is regulated by a rheostat 132. The temperature produced by the heating elements 122 may be controlled within close limits so as to insure the proper degree of fluidity of the wax carbon when it is transmitted to the ink roller 68.

35 The amount of carbon to be transmitted to the ink roller and consequently the thickness of the final deposit printed on the paper is regulated by an adjustable doctor blade 135, Figs. 2, 3 and 4. The support for the blade includes a bar 136 having trunnions 137 journalled in the side plates of the inking mechanism and a member 138 which is drawn by bolts 139 against the member 136 to clamp the blade 135 in position. The adjustment for the blade with reference to the roller 121 comprises a U-shaped member 141 rigid with each trunnion 137 and a bolt 142 threaded through a lug 143 on a member 144 which is normally held stationary in a fixed position. By turning the bolt 142, the U-shaped member and the doctor blade carrier 40 may be adjusted on its trunnion toward or away from the roller 121. The member 144 is pivoted to the trunnion 137 of the doctor blade structure and has a slot 145 engaging over a pin 146. This pin is rigid with a nut 147 and a threaded rod 148 which is screwed into a threaded hole in

the frame member 149. After the doctor blade has been assembled in position, the member 144 is firmly secured in position by a thumb nut 151 threaded on the outer end of the pin 146, the thumb nut being tapered to fit into a tapered recess in the side of the member 144. When it is desired to move the doctor blade structure for cleaning or other purposes the thumb nut 151 is loosened and the whole structure may then be swung as a unit around the trunnion 137 by means of the handle 152. When the unit is returned to its effective position the tapered end on the thumb nut will cooperate with the tapered recess to lock the unit in correct position without any resetting or adjusting of the parts. The mechanism described and shown in the drawings for adjusting the doctor blade and holding it in adjustable position may be duplicated at both ends of the doctor blade structure, although the member 136 holding the doctor blade may be so rigid that such duplication may not be necessary. The easily accessible adjustment afforded by the bolt or bolts 142 makes it convenient to regulate the operation of the doctor blade with great nicety to control the supply of carbon to the printing plate to print carbon spots in which the carbon is of any thickness desired.

The rollers 101, 102, 121 and 68 are all driven through gearing which causes rollers 102 and 101 to be driven at a speed which is lower than the speed of rotation of the other rollers mentioned. This gearing is shown in Figs. 5 and 9. The driving impulse comes from a gear 154 rigid with the plate cylinder 35 and which is driven by a gear rigid with the impression cylinder 34, the latter gear being in mesh with and driven by the small gear 33 previously mentioned. Meshing with the gear 154 is an idler gear 155 which drives two other idler gears 156 and 157. The gear 157 is in mesh with a gear 158 rigid with the heated roller 121 and the gear 158 is in turn in mesh with a gear 159 rigid with the ink roller 68. Rigid with the gear 158 is a smaller gear 161 which drives a gear 162 rigid with the font roller 101. The gear 161 is about half of the diameter of the gear 162, thereby causing the roller 101 to turn at about half of the speed of the rollers 121 and 68. Rigid with the gear 162 is a small gear 163 which drives a gear 164 rigid with the lower heated roll 102. The speed of the rollers 101 and 102 is reduced because the lower speeds are sufficient to cause the rollers to lift the carbon from the supply pan 95 and maintain the pool 103 at a uniform level from which the roller 121 and inking roll 68 are supplied. However, there is an overflow from the pool which, due to the higher peripheral speed and direction of rotation of the heated roller 121, will be over the top of the heated roller 102 and back into the font 92. The roller 101 and the heated rollers 102 and 121 therefore cooperate to keep the carbon wax in constant motion so that it cannot chill or stiffen in parts of the font, thereby contributing to uniformity of temperature and consistency of the wax in the font.

The carbon heating and applying mechanism is, as before stated, so constructed that it may be moved as a unit relative to the plate cylinder 35. The rollers of the mechanism are all journaled in a frame construction which is rigid with the carbon supply pan and the heating units therefor. The entire unit slides upon tracks 165 which are pivoted at 166. The entire inking unit may be slid along these tracks until 75

arrested by beveled stops 167 and then secured in position by bolts 168. This movement is facilitated by rollers 171 which rotate on tie rods 94 of the font structure, the tracks in which the rolls run being recessed so that there is a slight drop of the inking mechanism as a unit relative to the tracks 165 as the stops 167 are engaged.

10 The tracks 165 are normally held level by a toggle mechanism hereinafter described. When it is desired to remove the inking mechanism as a unit, the bolts 168 are removed and the entire unit, including the supply pan and all the rollers, may be then slid out or removed entirely to a table or stand. It may then be cleaned or simply left out of normal position without any change of the adjustments of the various parts so that when it is restored to the position in which it is shown in Fig. 1, normal printing may be resumed without difficulty.

15 When the carbonizing or inking unit is moved out as just described, the gears 153 and 157 may become disengaged. In order to facilitate remeshing these gears, the shaft 116 to which the roller 101 is attached is provided with a hand-wheel 170, Fig. 1, which can be operated to set the gear 150 so that it will mesh properly with the gear 157. The hand-wheel 170 may also be used to turn all of the rollers in the inking or carbonizing unit when the rollers are being cleaned.

20 The printing press illustrated has a throw-off mechanism by which the plate cylinder 35 may be moved out of printing relation with the impression cylinder whenever desired. This mechanism is shown in Patent No. 1,789,420, issued January 20, 1931, to Peter Aitchison. It comprises a cam 171 (Figs. 1 and 11) secured to the shaft 172 to which the plate cylinder 35 is attached, this cam operating a lever 173 pivoted at 174 to reciprocate a link 175, a roller on the lever 173 being held against the cam by a spring 175a. The link 175 is supported at an intermediate point by a rod 176 passing through a lug 177 pivoted in a boss 178 projecting from link 175. Springs 179 and 179a (see also Fig. 14) on the rod 176 cooperate with collars 180 on the rod and with the lug 177 to hold the link 175 in the position at which it is shown in the figures while the press is running, the link in this position being given an idle movement by the cam 171.

25 The rod 176 extends from a link 181 (Fig. 1) having its upper end pivoted at 182 to a member 183 which is in turn pivoted on a bracket 184 mounted on the main side frame of the press. Rigid with the member 183 is a manually operable handle 185 which may be used to swing the member 183 over top center from the position in which it is shown in Figs. 1 and 14 and under bottom center until a stop 186 on the member 30 strikes the lower edge of the link 181. This will thrust the link 181 and its springs and spring rod 176 downward and will swing the link 175 correspondingly so that reciprocation of the link 175 will become effective to operate the plate cylinder throw-off mechanism.

35 The shaft 172 to which the plate cylinder is attached is rotatably mounted in blocks or chocks 187, Fig. 12, which are mounted for sliding movement in a housing 188 secured to the machine frame. When the plate cylinder is in cooperative relation with the pressure cylinder the chocks 187 are held in the determined relation by cams 189 on shafts 190 against the tension of springs 191. When the plate cylinder is to be thrown off, the shafts 189 and the cams thereon are

turned to relieve the springs 191 whereupon the springs will slide the chocks 187 to carry the plate cylinder out of printing relation with the pressure cylinder.

The positions of the cams 189 and consequently the relation of the plate cylinder to the pressure cylinder is controlled by the manually operable handle 185, Figs. 1 and 14, and the parts connected thereto. When the handle is in position in which it is shown in the drawings the connection between the link 181 and the element 183 is a trifle past center so that the handle and the assembly will remain in the position shown during the idle reciprocation of the link 175, but when the handle is turned (clockwise, as viewed in Fig. 14) until the stop 185 engages the edge of the link 181, the upper end of the link 175 will be depressed. The handle 185 and connections are held in either of the two positions by tensioning one or the other of the two springs 179 and 179a as hereinafter explained. In its depressed position an upward thrust of the link 175 will actuate connections to turn the cams 189, thereby freeing the springs 191 to move the plate cylinder away from the pressure cylinder. The connections for doing this include a pair of rollers 192 and 193 (Figs. 14 and 15) mounted on studs 194 and 195 secured in a plate 196 keyed on a shaft 197 extending across the machine. A plate 198 is held by nuts 199 in position to hold the rollers 192 and 193 on the studs 194 and 195. Also keyed on or attached to the shaft 197 are arms 201 and 202, one at each side of the machine, which are pivotally connected to links 203 and 204 which in turn are pivotally connected at their lower ends to arms 205 and 206 secured to the throw-off cam shafts 190. When the manually operated handle is turned as above described from the position in which it is shown in Fig. 14, reciprocation of the link 175 will cause the shoulder 207 on the link to engage the roller 193 and turn the arms 201 and 202 clockwise as viewed in Fig. 14, thereby drawing up on the links 203 and 204 to rotate the plate cylinder throw-off cams 189 clockwise, as viewed in Fig. 12, to permit the springs 191 to move the plate cylinder to its ineffective position. When the handle is restored to the position at which it is shown in the drawings, the shoulder 208 on the link 175 will engage the roller 192 and rotate the plate throw-off cams 189 back to the position in which they are shown, thereby moving the plate cylinder into printing relation with the pressure cylinder.

The resistance for tensioning the springs 179 and 179a on the spring rod 176 is afforded by engagement of a finger or tongue 211 on the end of the link 175 which, during a reciprocation of the link, rides idly against one or the other of the rollers 192 or 193. In the position in which the parts are shown in Figs. 1 and 14, the spring 179 is under tension to hold the tongue 211 against the roller 192 and that tension also serves to hold the handle 185 and connected parts in the positions in which they are shown in the figures referred to.

The throw-off cams 189 for the plate cylinder are, as before stated, attached to shafts 190. These are, as shown in Figs. 11 and 12, short shafts journaled in links 212 and 213 suspended from bosses 214 on brackets 215. Mounted in the lower ends of the links are bolts 216 passing through elongated holes in brackets 217 attached to the machine frame. These elongated holes are to permit the adjustment of the links around

their upper pivots to regulate the printing pressure of the plate cylinder relative to the pressure cylinder, the adjustment consisting of headed screws and lock nuts 218 in the brackets 217 cooperating with the cross bolts 216.

The plate cylinder throw-off mechanism described is employed in controlling a throw-off for the inking or carbonizing unit whereby when the plate cylinder is thrown out the inking mechanism will also be thrown off. The extent of movement of the inking throw-off may be just great enough to accommodate the throw-off movement of the plate cylinder, leaving the ink roller 68 still in inking contact with the printing plate on the cylinder, but it is preferred to have the throw-off carry the ink roll 68 completely out of such contacting position when the plate cylinder is out of printing relation with the pressure cylinder.

The inking throw-off causes the entire inking unit to swing about the pivot 166 upon which, as before stated, the tracks 165 are mounted. Normally the entire inking unit is supported in the inking position in which it is shown in the drawings by a pair of toggles, one under each of the tracks 165, Figs. 1, 1a and 11, each toggle consisting of a link 221 pivoted at one end to the rail 165 and having its other end pivoted at 222 between arms extending from units 223 secured to a shaft 224. Springs 225 on spring rods connected at one end to the pivotal connection between the arms 221 and 222 and guided at the other end in the rod upon which the tracks 165 are pivoted, normally tend to hold the toggle past center, in which position a stop shoulder 227, Fig. 1a, is in engagement with a flat surface 228, thereby holding the tracks 165 and everything supported by them in elevated position. When the toggle is broken to allow the tracks and everything supported thereon to drop down around the pivot 166, the toggle parts are in the position in which they are shown in Fig. 1a. In this position a shoulder 229 on the link 221 will be in engagement with the flat surface 228 between the arms on the elements 223. When the tracks or rails 165 are lifted to restore things to normal the springs 225 will throw the toggle parts over center and the inking mechanism will then be supported in operating relationship with the plate cylinder.

The toggle is broken for the purpose just stated by a link 231, Figs. 1 and 11, which is pivoted at its upper end to the arm 206 forming a part of the plate cylinder throw-off mechanism previously described. When the link 204 connected to the arm 206 is drawn up by operation of the cylinder plate throw-off mechanism, the link 231 will likewise be drawn up and will act through an arm 232 rigid with the shaft 224 to swing the toggle parts to the positions in which they are shown in Fig. 1a. This will allow the entire inking mechanism to swing on the pivot 166 and will, among other things, swing the inking roll 68 well out of contact with the printing plate cylinder even though that cylinder may have been moved out of printing relation with the impression cylinder 34. The connections, including the links 203 and 231 will, when the plate cylinder is thrown in, restore the arm 232 and the toggle parts to the positions in which they are shown in Figs. 1 and 11, and the inking roller 68 will then be in correct position to apply carbon to the printing plate. Return of the toggle mechanism to normal from the position in which it is shown in Fig. 1a, is assisted by the springs 225.

When it is desired to operate the toggle mechanism independently of the plate cylinder throw-

off mechanism, a locking screw or bolt 233 extending through a bayonet slot 234 in the link 231 and threaded into the arm 232 may be loosened and the lowered end of the link 231 then swung to bring the long side of the bayonet slot in alignment with the locking screw. The downward thrust imparted to the link 231 when the plate cylinder is thrown in will then be an idle one. The arm 232 may then be actuated by means of a handle 235 to straighten the toggles. This will bring the short side of the bayonet slot in line with the locking screw 233 and the arm 232 and the link 231 may then be reconnected.

While the heated font 92 and the heated rollers 101, 102 and 121 heat the carbon until it has about the proper consistency, means are provided for applying heat to the carbon on the printing plate and to the printing plate in order to prevent any substantial chilling of the carbon before it is applied to the paper. This is effected by electrical heating units of the strip type which extend the full width of the printing plate. The arrangement of these heaters is best shown in Fig. 10. In the construction illustrated there are five strip heaters 241 extending across the face of the plate cylinder and three more of the strip heating units 242 below the plate cylinder. A hood 243 attached to the machine framing confines the heat from the strip heaters 241 and insures application of the heat to the plate cylinder. A similar shield 244 is provided for the lower set of strip heaters 242. In order to make lower strip heaters 242 accessible, they are supported between arms 245 pivoted at 246 and held in the position in which they are shown by latches 247 cooperating with pins 248 on the arms 245.

The heaters 241 and 242 are in the same circuit, that circuit being controlled by a switch 251, Figs. 20 and 21, and the volume of heat is controlled by a manually-operated rheostat 252. As shown in the figures last mentioned, the current for all of the heating elements is turned off and on by a master switch 253 and the current for the ink font 92, the heated rollers 102, 121 and the heating units 241 and 242 for the plate cylinder may be independently turned on and off and may also be independently regulated so as to get the proper degree of heat at each point of the mechanism where heat is required.

From the foregoing it is believed to be clear that the printing plate on the plate cylinder may be constructed to provide any desired number of printing faces, and that these faces may be constructed to print carbon spots of any desired extent or shape and in any desired locations on the paper. Some of these carbon spots are illustrated at 255 and 256 of Fig. 18 and others at 257 and 258 of Fig. 19. It is also believed to be clear that the doctor blade 135, by its sensitive adjustment mechanism is capable of regulating the thickness of the carbon deposits in printing the spots according to varied requirements. The consistency of the carbon can be controlled and maintained by the described system for applying and regulating the heat at all critical points so that uniformity and efficiency of operation are insured.

The font and roller mechanism for supplying the carbon to the printing faces has obvious advantages, not the least of which is that the font and the entire roller mechanism may be moved or removed as a unit without disturbing any of the adjustments, and that the entire font and roller mechanism may be thrown off so as to prevent application of carbon to the printing plate

when printing is not to be affected. This keeps the printing plate free of excess carbon and further contributes to proper operation of the apparatus.

5 In removing the font and all of the roller mechanism carried with it, the current connections for keeping the font and the rollers 102 and 121 may be left on to facilitate the cleaning or the heat may be applied by operation of the 10 switches to the font alone or to either one of the rollers. Further, the impression roller 35 may be run while the heat is applied by the heating elements 241 and 242 to warm up the printing plate before printing is begun, this being done 15 while the plate cylinder is in its thrown-off position. In moving it to this position the gears between it and the impression cylinder 34 are not disengaged, so that the two cylinders will turn in their normal relationship even though there is no printing contact between them. It will be recalled that while the plate cylinder 35 is thrown off the inking mechanism is likewise thrown off so that the printing faces on the printing plate will not be inked during this preliminary warming-up operation of the printing plate.

25 While the mechanism involved has been described in considerable detail, it will be apparent to those skilled in the art that the mechanism can be changed in various respects, and it is not 30 the intention to be limited by anything hereinabove set forth except to the extent indicated by the claims which follow.

What is claimed is:

1. In a machine of the class described, a font 35 for containing a supply of melted wax carbon, and a pair of oppositely driven parallel rollers mounted in close relation in the font cooperating mutually and with the walls of the font to create and maintain a pool of wax carbon at a constant level 40 above the level of the wax carbon in the font.

2. In a printing machine having a rotary printing cylinder carrying printing elements and a rotary impression cylinder cooperating therewith, an inking mechanism for supplying a printing composition to the printing elements which includes a heated font for containing a fluid supply of said composition, a pair of oppositely driven rollers in said font cooperating to create and maintain a pool of said fluid composition held 45 by the rollers and the walls of the font at a constant level above the level of the supply in the font, a heated supply roller mounted for rotary movement in the walls of the font and having its periphery rotating in and lifting printing composition from said pool, an inking roller supplied 50 with printing composition by contact with the supply roller and applying said composition to the printing elements at each rotation of the printing cylinder, and a doctor blade cooperating with the supply roller to regulate the amount of 55 printing substance supplied to the inking roller.

3. In a printing machine having a rotary cylinder carrying a printing element, a mechanism for applying a printing substance to the printing faces of the printing element which includes a heated font for containing a supply of printing substance in fluid condition, a pair of oppositely driven rollers in said font cooperating to create and maintain a pool of said substance defined by 65 the rollers and the walls of the font, said pool being above the level of the substance in the font, a heated supply roller mounted for rotary movement in the walls of the font and having a part of its periphery rotating in and drawing 70 printing substance from said pool, an adjustable 75

doctor blade cooperating with said heated roller to regulate the thickness of the printing substance on said roller, and an inking roller turning in contact with said heated roller to receive printing substance therefrom and in contact with the printing faces of the printing element to apply the printing substance thereto.

4. In a printing machine having a rotary printing cylinder carrying a printing plate on its periphery, means for inking said plate comprising an inking roller making contact with the printing faces on the printing plate, a heated supply roller for supplying printing fluid to the inking roller, an adjustable doctor blade cooperating with the heated roller for regulating the amount of printing fluid supplied by said heated roller to the inking roller, a heated font for containing a supply of printing fluid, a pair of oppositely driven rollers mounted in said font and cooperating to establish and maintain a pool of printing fluid confined by the rolls and the walls of the font, said pool being above the level of the fluid in the font and in contact with the periphery of the transfer roller.

5. In a printing machine having a rotary printing cylinder carrying printing elements constructed to provide printing faces of the desired configuration and a pressure cylinder cooperating with the printing cylinder, an inking roller for applying a printing material to said printing faces, a supply roller and a doctor blade cooperating therewith for supplying the printing material to the inking roller in regulated amounts, a font for containing the supply of printing material, and a pair of oppositely driven rollers in the font cooperating to establish and maintain a pool of the printing material between them and above the level of the material in the font, the lower periphery of the supply roller turning in and drawing printing material from said pool.

6. In a printing machine having a rotary impression cylinder and a rotary plate cylinder carrying a printing plate constructed to provide printing faces of the desired configuration cooperating with the impression cylinder, a mechanism for applying melted wax carbon in fluid condition to said printing faces which includes an ink roll carrying melted wax carbon in fluid condition, a font for containing a supply of wax carbon, means for heating the font to raise the wax carbon to a temperature above its melting point, a heated supply roller turning in contact with the ink roller for supplying melted wax carbon to the ink roller, means in the font for supplying melted wax carbon to the surface of the supply roller, and means cooperating with the supply roller to regulate the amount of wax carbon supplied to the ink roll.

7. In a printing machine having a rotary impression cylinder and a rotary plate cylinder carrying a printing plate constructed to provide printing faces of the desired configuration cooperating with the impression cylinder, a mechanism for applying melted wax carbon in fluid condition to said printing faces which includes a driven applying roller having its periphery making contact with said faces during each rotation of the plate cylinder, a heated supply roller for supplying wax carbon in melted condition to the applying roller, a font for containing a supply of wax carbon heated above its melting point, means in the font for lifting the melted wax carbon into contact with the periphery of the supply roll, means cooperating with the supply roll for regulating the amount of wax carbon deliv-

ered by the supply roll to the applying roll, and means for applying heat to the wax carbon on the printing faces to keep the wax carbon fluid until the printing impression is made.

5 8. In a printing machine having a rotary printing cylinder carrying printing elements and a rotary impression cylinder cooperating therewith, an inking mechanism for applying a colored printing composition to the printing elements which includes a heated font for containing a fluid supply of said composition, a pair of oppositely driven rollers in said font cooperating to create and maintain a pool of said composition supported between the rollers and the walls of the font at a constant level above the level of the supply in the font, one of said rollers being heated, a heated supply roller mounted for rotary movement in the walls of the font and having its periphery rotating in and lifting printing composition from said pool, an inking roller supplied with printing composition by rolling contact with the supply roller and applying said composition to the printing elements by rolling contact therewith at each rotation of the printing cylinder, a doctor blade cooperating with the supply roller to regulate the supply of printing composition to the inking roller and printing elements, and means for applying heat to the printing composition on the printing elements to maintain said composition in fluid condition until the printing impression is made.

25 9. In a machine of the class described, a rotary printing couple normally in printing relation, manually controlled means for moving one member of the couple out of printing relation with the other at the end of a run of printing operations, apparatus including an inking roller normally in position to be effective to apply hot wax carbon to the printing member of the couple, and means controlled by the aforesaid manually controlled means for moving the inking roller out of contact with the printing member of the printing couple when the members of said couple are moved out of printing relation.

40 10. In a machine of the character described, a plate cylinder carrying a printing plate and a co-operating impression cylinder, a throw-off mechanism for moving one of said cylinders into and out of printing relation with the other cylinder, manipulative devices connected to and operable to control operations of the throw-off mechanism, an inking mechanism comprising an ink roller normally held in position to ink the printing plate at each rotation of the plate cylinder, a throw-off mechanism for the inking mechanism operable to move the inking roll away from the plate cylinder, and connections to the aforesaid manipulative devices for controlling operations of the inking mechanism throw-off.

45 11. In a machine of the character described, a plate cylinder carrying a printing plate and a co-operating impression cylinder, a throw-off mechanism for moving the plate cylinder out of printing relation with the impression cylinder, an inking mechanism comprising an inking roller for applying a printing composition to the printing plate, means normally holding the inking mechanism in position for the inking roll to make inking contact with the printing plate at each rotation of the plate cylinder, an inking mechanism 50 throw-off for operating said means to move the inking mechanism to carry the inking roller out of inking relation with the printing plate, manipulative devices, and connections controlled by the manipulative devices for simultaneously op-

erating the plate cylinder and inking mechanism throw-offs.

12. In a machine of the class described, a printing member, means for supplying hot wax carbon to the printing member including a font, an inking roller and rollers mounted in and on the font for transmitting the wax carbon from the font to the inking roller, pivoted tracks upon which the font is slidably supported, toggles connected to the tracks normally holding the tracks in such position with respect to their pivots that the inking roller will be held in inking relation with the printing member, a manipulative device, and connections controlled by said manipulative

device for actuating the toggles to turn said tracks on their pivots to carry the inking roller out of inking relation with the printing member.

13. In a machine of the class described, a heated font for containing a supply of melted wax carbon, and a pair of oppositely driven parallel rollers, at least one of which is heated, mounted in close relation in the font cooperating mutually and with the walls of the font to create and maintain a pool of melted wax carbon at a substantially constant level above the level of the wax carbon in the font.

FRANK C. MARQUARDT.
